UNITED STATES PATENT OFFICE.

WILLIAM R. FORSYTH, OF SWAMPSMOTT, MASSACHUSETTS, ASSIGNEE TO CROSS ROD AND TACKLE COMPANY, OF LYNN, MASSACHUSETTS, A CORPORATION OF MASSACHUSETTS.

GOLF-CLUB SHAFT.

Application filed March 21, 1921. Serial No. 454,084.

To all whom it may concern:

Be it known that I, WILLIAM R. FORSYTH, a citizen of the United States, residing at Swampscott, in the county of Essex and 5 State of Massachusetts, have invented a new and useful Golf-Club Shaft, of which the following is a specification.

This invention, while of general application to the shafts of golf clubs, is of particular utility in connection with those such 10 as drivers or brassies, which are used for obtaining distance on the links.

The present invention has for its object to provide a golf shaft which is light, strong, 15 of uniform feel to the player in different clubs, and with which maximum distance may be obtained.

To this end, the improved golf shaft is provided with a plurality of longitudinally 20 extended sections or members of bamboo or like cane, which members are arranged with their hard layers forming the outer surface of the shaft and firmly secured together.

In the accompanying drawings, a particular embodiment of the invention is illustrated, Figure 1 being a broken perspective view of a golf club, in which my improved shaft is included; Fig. 2, a transverse section through said shaft; and Fig. 3, a broken 30 longitudinal section on the line 3—3 of Fig. 2.

The shaft A herein shown, which carries the head B, and has a grip portion 10 of maximum diameter by which the club is 35 grasped, gradually tapers longitudinally in one direction from the grip to a contracted waist portion 11, and again tapers in the opposite direction to the end 12, ordinarily of less diameter than the grip. The end 12 40 in the shaft herein illustrated is adapted for insertion in the socket 13 of the head B, and will be hereinafter referred to as the head end of the shaft. The head B is herein represented as of metal, but it may be of wood 45 or other suitable material.

The shaft is constructed of a plurality of longitudinally extended sections or members generally sector-shaped considered transversely, continuing unbroken from the grip 50 through the waist to the head end, and formed from bamboo or like cane, having at the outside a relatively thin, closely packed layer a, of great hardness, strength and resilience, and which will be hereinafter referred to as the hard layer, and having an

inner softer layer b commonly known as the pith layer.

The longitudinally extended sections or members of the golf shaft are made from strips of the bamboo or like cane, which 60 strips are rendered substantially smooth on their inner and outer surfaces, and when the cane is not of sufficient thickness two strips 14, 15 are glued or otherwise firmly secured together with the hard layer a of the inner strip in contact with the pith layer b of the outer strip, to form a combined strip from which the shaft members shown in Fig. 2 may be formed. As illustrated in Fig. 2, the inner strip 14 of each shaft section or member is of substantially triangular cross-section, with the apices of the triangles located at the axis of the shaft, and the angles between the sides are such that they combine to form a hexagon. The outer strip 15 70 of each of the shaft members or sections is substantially a trapezoid. The outer sides of the outer sections, that is the bases of the trapezoids, depart from straight lines, being 75 slightly curved, since they preferably follow the natural contour of the outer layer of the cane. The outer sides of the inner strips may be somewhat reduced along the centers to give substantially plane surfaces to facilitate joining to the outer strips. This reduced portion preferably does not go entirely through the hard layer.

The strips comprising a shaft member or section are glued or otherwise firmly secured together, and may be cut from the 80 cane in the form in which they are assembled, and they may be bent or molded, so that when the shaft members are brought together to form a shaft with enlarged ends and contracted waist, as herein shown, the 85 continuity of the hard layers over the exterior of both strips will be maintained both longitudinally and circumferentially of the shaft and produces a symmetrical relation between the shaft members at all transverse 90 sections, the hard layer of the inner strip being substantially midway between the axis of the shaft and the outer hard layer thereof, as represented in Fig. 3. There is thus produced a shaft of extreme lightness and 95 almost absolutely straight grain, of a high degree of continuity, especially in the best portions of the cane, and of remarkable 100 strength.

The natural resilience of the cane which 110

has a higher rate and a greater amplitude of vibration than hickory or like wood largely used in the manufacture of golf shafts, is of decided advantage in a golf shaft, as 5 it imparts to the golf shaft the desirable snap due to the quicker return of the shaft from its rearward deflection when the club head meets the golf ball on the downstroke of the club, which results in the golf ball 10 being propelled a greater distance, especially in the case of the driver, brassie, or like club having a wooden head. Furthermore the bamboo or like cane golf shafts herein described can be made uniform, so that when 15 incorporated in the different clubs, including the irons, they have the same feel to the player, which is highly desirable, as it enables the player to use each club with the same confidence.

20 By the term bamboo as used in the claims, I desire to be understood as using the word generically so as to include natural canes of this class. In the present instance, the invention is shown in a golf shaft which is inclined in one direction from the grip end to the waist portion and is inclined in the opposite direction to the head end and further is used with a socketed head, but it is not desired to limit the invention to this particular construction or shape of shaft.

I claim:

1. A golf club shaft having a plurality of longitudinally extended sections or members of bamboo cane firmly secured together and arranged with the hard layer of the cane forming the exterior surface of the shaft.
2. A golf club shaft having a plurality of longitudinally extended sections or members of bamboo cane provided with substantially smooth exterior surfaces and firmly secured together with the hard layer of the cane forming the exterior surface of the shaft.
3. A golf club shaft having a plurality of longitudinally extended sections of bamboo cane firmly secured together and each comprising a plurality of strips of bamboo cemented together with the hard layer of the inner strip affixed to the pith layer of the outer strip and with the hard layer of the latter strip forming a section of the outer surface of the shaft.
4. A golf club shaft comprising a plurality of longitudinally extended sections of bamboo cane arranged in a plurality of layers between the exterior and the axis of the shaft and with the hard portion of the outer layers forming the exterior surface of the shaft.
5. A golf club shaft comprising a plurality of longitudinally extending sections of bamboo arranged with the hard layers of said sections on the exterior of said shaft.
6. A golf club shaft having between its ends a contracted portion and comprising a

plurality of longitudinally extended sections 65 of bamboo cane with the hard layer thereof arranged toward the exterior and formed to furnish the contracted portion while maintaining the continuity of the hard layer over the outer sides of the sections. 70

7. A golf club shaft having a grip, head end and intermediate waist portion, and comprising a plurality of sections of bamboo extending continuously from the grip to the head end with the hard layer at the 75 exterior of the shaft, said sections being formed to furnish the varying contour of the grip, waist and head end while maintaining the continuity of the hard layer over the exterior of the shaft. 80

8. A golf club shaft having a grip, a head end and an intermediate waist portion, and comprising a plurality of sections of bamboo arranged in inner and outer layers extending continuously from the grip to the head end with the hard surface at the exterior of both layers, said sections being formed to furnish the varying contour of the grip, waist and head end while maintaining continuity of the hard surface over 90 the exterior of the layers. 95

9. A shaft for golf clubs having a plurality of members of bamboo or like cane substantially triangular in cross section and cemented together with the apices of the triangles forming a substantially straight center or axial line and with their harder outer surfaces tapering in opposite directions. 100

10. A shaft for golf clubs having a plurality of members of bamboo or like cane substantially triangular in cross section and firmly secured together with the apices of the triangles forming a substantially straight center or axial line and with their harder outer surfaces tapering in opposite directions. 105

11. A shaft for golf clubs having a plurality of members of bamboo or like cane firmly secured together with their harder outer surfaces tapering in opposite directions and of substantially uniform thickness for the length of the shaft. 110

12. A shaft for golf clubs having a plurality of members of bamboo or like cane firmly secured together with their harder outer surfaces tapering in opposite directions, of substantially uniform thickness for the length of the shaft and substantially circular in cross section. 115

13. A shaft for golf clubs having a plurality of members of bamboo or like cane secured together about a common center with the harder layer of the cane forming the outer surface of the shaft and provided with oppositely tapering portions. 120

14. A shaft for golf clubs having a plurality of members of bamboo or like cane firmly secured together and provided with a

relatively hard layer of substantially uniform thickness and with a pith layer of different thicknesses with that of the least thickness between its ends.

- 5 15. A shaft for golf clubs having a plurality of members of bamboo or like cane firmly secured together and comprising an

outer strip of cane and an inner strip of cane having its pith layer reduced in thickness between its ends.

Signed at Lynn, in the county of Essex and State of Massachusetts, this fifteenth day of March, 1921.

WILLIAM R. FORSYTH.
